FIG. 1

FIG. 2

To all whom it may concern:

Be it known that I, Gilman A. Helland, a citizen of the United States of America, residing at Minneapolis, in the county of Hennepin and the State of Minnesota, have invented a new, original, and ornamental Design for a Chair, of which the following is a specification reference being had to the accompanying drawing, forming a part thereof.

Fig. 1 is a perspective view showing front and side elevations of the chair, with its covering material, which forms a part of the seat and back portions thereof, shown by means of dotted lines.

Fig. 2 is a perspective view showing side and rear

elevations of the chair, with its covering material, which forms a part of the seat and back portions thereof, shown by means of dotted lines.

I claim:

The ornamental design for a chair, substantially as shown and described.
